United States Patent Office

Des. 187,311
Patented Feb. 23, 1960

187,311

AIRCRAFT

Robert B. Whitney, Malibu, Calif.

Application December 3, 1956, Serial No. 44,035

Term of patent 14 years

(Cl. D71—1)

Fig. 2

Fig. 3

Figure 1 is a side elevational view of an aircraft, showing my new design;

Figure 2 is a top plan view of the aircraft shown in Figure 1; and,

Figure 3 is a front elevational view of the aircraft shown in Figure 1.

The dominant features of my new design are shown in solid lines in the drawing.

I claim:

The ornamental design for an aircraft, as shown and described.
